DRY POWDER FIRE EXTINGUISHER

Jere B. Fleming and Martin B. Fleming, New York, N. Y.

Application March 3, 1955, Serial No. 491,857

2 Claims. (Cl. 169—31)

This invention relates to a dry powder fire extinguisher and more particularly to a diaphragm type of fire extinguisher having a depressible valve plunger provided with a cutting edge.

It is an objective of this invention to provide a dry powder fire extinguisher of inexpensive construction.

It is another objective to provide a high pressure dry powder fire extinguisher having a manually depressible plunger adapted to cut a sealing diaphragm.

These and other objective of this invention will become apparent upon reading the following descriptive disclosure taken in conjunction with the drawing in which:

Fig. 1 is a top plan view of a fire extinguisher.

Fig. 2 is a side elevation view taken on line 2—2 of Fig. 1 and broken away in part to show the fire extinguisher valve,

Fig. 3 is a front plan view of the fire extinguisher cap showing a bayonet slot in a depending wall of said cap,

Fig. 4 is a front view showing the cap in closed position and showing in dotted outline cap in the open or operative positive,

Fig. 5 is a longitudinal section view of the extinguisher valve head assembly showing the plunger disposed in cut-through relationship to the sealing diaphragm,

Fig. 6 is a fragmentary view cut-through portion of the extinguisher of Fig. 5 but taken at right angles thereto,

Fig. 7 is a cross section view of a modified dry powder fire extinguisher showing a squeeze grip means for actuating the valve plunger and

Fig. 8 is a view taken on line 8—8 of Fig. 7.

The dry powder fire extinguisher of this invention employs a high pressure resistant container 10 which is provided with an inlet gas valve 11 such as is used on automobile tire tubes and a high pressure gauge 12. The dry powder fire extinguisher material used is powdered sodium bicarbonate, and the high pressure in the container 10 is preferably obtained with nitrogen gas, but other inert gases at about 150 pounds per square inch are operable.

The container 10 is provided with a mouth in its top curvatured portion into which there is fixedly disposed as by welding thereto, a threaded tubular valve seat 13. The valve seat 13 is provided with a circular shoulder 14 upon which there is disposed a syphon tube 15 having a perpendicularly disposed flange 16X.

A sealing diaphragm 16 of suitable metal thickness and pierceable quality is disposed on the flange 14 and an O-ring 17 is disposed upon the diaphragm 16 adjacent the rim thereof.

A screw threaded tubular valve plug 18 is provided with screws threads 19 adapted to engage the mating screw threads of valve seat 13. The passage of plug 18 is provided with a tubular plunger 20 moveably disposed therein. The plunger 20 is provided with a cutting edge 21 on a beveled terminal end having preferably a lesser diameter than that of the main section of passage 20.

2

The plunger 20 is fixedly secured to a cap 22 having a partial depending skirt 23.

The skirt 23 of cap 22 is provided with a horizontal slot merging at its right end with a vertical slot to provide a bayonet slot 24. The plunger 20 is provided with a slot 25 suitably disposed relative to the bayonet slot 24.

The plug 18 is provided with an exit orifice 26 in which a nozzle 27 having a flattened port is fixedly disposed as by press fitting therein.

The fire extinguisher is further provided with a handle 28 of U-shaped cross-section fixedly secured as by welding to plug 18.

Figs. 2 to 4 show the valve in the non-operative position having an unpunctured sealing disk 16. To operate the valve cap 22, which is normally taped down with friction tape (not shown) the tape is ripped off and the cap rotated leftwardly (Fig. 4) until nozzle 27 hits vertical wall 24X (Fig. 3) in which position slot 25 of plunger 20 is in line with orifice 26 of plug 18.

Next, a sharp blow with the palm of the hand on cap 22 forces said cap 22 downwardly causing cutting edge 21 to pierce through diaphragm 16 (Figs. 5 and 6). The downward movement of cap 22 is arrested by nozzle 27 engaging the top edge of the vertical slot section of bayonet slot 24 (Fig. 4) (dotted outline). The cap 22 is captively held in place over plug 18 because nozzle 27 functions also as a locking pin. In this operative position slot 25 is in register with orifice 26.

After sufficient dry powder has been discharged to extinguish the fire the cap 22 may be rotated back to its original position in the horizontal section of the bayonet slot 24 to cut-off the dry powder stream of material.

Turning to Figs. 7 and 8 there is shown a modified extinguisher wherein the valve plunger 20 is depressed by means of a moveable hand operated U-shaped squeeze grip plate 29.

In this modified form the palm depressible bayonet slotted cap 22 is eliminated and the plunger 20X is hingedly secured to the side walls of the U-shaped squeeze grip plate 29 by means of a hinge pin 30 having a pair of hemispherical ends 31 for preventing the pin 30 from falling out.

The plunger 20X is further provided with an aperture suitably disposed from the top end thereof and through which a lock pin, for example a cotter pin 32, is disposed. The cotter pin 32 is provided with a wire pull cord 33 so that in the operation of the modification shown in Figs. 7 and 8 the cotter pin is pulled out of the plunger prior to squeezing the plunger downwardly and through diaphragm 16.

As shown in Fig. 7, the plunger 20X has a passage throughout substantially half its length and solid therabove, the cotter pin 32 and the hinge pin 30 being disposed in suitably disposed apertures in the solid part of the plunger 20X. The passage of the tubular plunger extends from the beveled plunger cutting edge 21 to a lateral aperture 34 adapted to register with orifice 26 of plug 18 when the plunger is fully depressed and in operating relationship with the container 10 for passage of a stream of powder from said container to orifice 26.

The grip plate 29 is journaled at its forward end by means of a swivel pin 35 to a moveable U-shaped lock plate 36 having a substantially flat terminus 37 having an aperture therein through which nozzle 27 passes thereby locking plate 36 to nozzle 27.

A compression coil spring 38 is disposed between handle 28 and grip plate 29 in punched dimple protruberances formed respectively therein.

In the operation of the modification shown in Figs. 7 and 8 depressing of plate 29 depresses the plunger 20X thereby cutting diaphragm 16 and simultaneously bringing

aperture 34 into registry with orifice 26 to permit the contents of the container 10 to stream from nozzle 27 and toward the fire to be extinguished.

This invention has been described by means of an embodiment but clearly other embodiments fall within the scope of the claims herein.

We claim:

1. A dry powder fire extinguisher comprising a pressure resistant container having a top aperture; a tubular seat element having an inner horizontally disposed circular shoulder, the passage of said seat element being threaded from the top to a point in spaced relation to said shoulder, said seat element having a circular groove in said passage at the end of said threads and also in suitable spaced relationship to said shoulder, said seat element being fixedly secured within the container aperture in a gas tight manner; a syphon tube having a suitable horizontally disposed flange at one end, said flange disposed upon said circular shoulder of said seat element to completely cover the shoulder area, said syphon tube extending in said container to a suitable point in spaced relationship to the container bottom; a metal pierceable sealing diaphragm disposed contactingly upon said syphon tube flange to completely engage the top of the syphon tube flange; a resilient O-ring disposed in said groove of said passage of said seat element and contacting said sealing diaphragm completely at its periphery; a tubular plug having a central smooth wall passage communicating adjacent the plug top with a lateral passage leading to the plug exterior surface, said plug having exterior screw threads at its bottom terminating at a circular groove in the bottom periphery of said plug, said plug being forcefully threaded into the threaded seat element so that the groove of the plug engages said O-ring in a gas tight manner and further forces said O-ring to engage said seat element and the sealing diaphragm adjacent thereto also in a gas tight manner; a slideable tubular plunger having

a central passage and a lateral passage communicating with the plunger passage adjacent the plunger top, said plunger being slidably disposed in the passage of the plug in contact with the plug passage wall, and extending above the plug top, said plunger having its lateral passage out of registry with the lateral passage of said plug in non-operative position, said plunger having a sloped bottom cutting edge disposed suitably above the sealing diaphragm and being of lesser diameter at its base adjacent the cutting edge to prevent jamming of the cut diaphragm metal with the plunger; and means for placing the lateral passage of said plunger into registration with the lateral passage of said plug with substantially a simultaneous cutting of said sealing diaphragm.

2. The apparatus of claim 1 wherein the means for placing the said lateral passages in registry comprises a bottom handle secured fixedly to said plug, a top handle secured swingably adjacent one end to the plunger portion extending above said plug, a nozzle disposed in the lateral passage of said plug, an apertured lock plate swingably secured to the end of the top swingable handle with said nozzle disposed in said aperture of said lock plate and a compression spring disposed between said top and said bottom handles to continuously urge them apart from one another.
